UNITED STATES PATENT OFFICE.

FREDERICK A. WOEHR AND JOSHUA T. FISK, OF ROCHESTER, NEW YORK; SAID FISK
ASSIGNOR TO SAID WOEHR.

FORMING PRESS.

Application filed September 29, 1919. Serial No. 327,089.

This is an invention in presses and more particularly, in machines of this character having operating devices adapted to be impressed upon the work for shaping or otherwise operating upon the material, one object of the invention being to provide a machine of the above character of a simple compact and rugged form of construction, capable of adaptation to a wide variety of uses and having a convenient and efficient method of operation for accomplishing the ends desired.

Another object is to provide in a machine of this nature a construction and mode of operation facilitating rapid production of work and maximum safety for the operator.

A further object is the provision of a machine of this type having means for heating the work engaging devices and for so manipulating the latter as to afford maximum efficiency of operation.

To these and other ends the invention consists in certain improvements and combinations of parts, all as will be hereinafter more fully described, the novel features being pointed out in the claims at the end of the specification.

In the drawings, Figure 1 is a side elevation of a machine embodying the present invention.

Figure 2 is a front elevation of the same.

Figure 3 is a sectional elevation through the casing substantially on the line 3^a—3^a of Figure 2, showing the operating parts.

Figure 4 is a similar sectional elevation but taken on the line 4^a—4^a of Figure 2.

Figure 5 is a section substantially on the line 5^a—5^a of Figure 1.

Figure 6 is a section on the line 6^a—6^a of Figure 1, showing the work table.

Figure 7 is a section on the line 7^a—7^a of Figure 3.

Figure 8 is a section substantially on the line 8^a—8^a of Figure 3.

Figure 9 is a section on the line 9^a—9^a of Figure 3.

Figure 10 is a section on the line 10^a—10^a of Figure 4.

Figure 11 is a section on the line 11^a—11^a of Figure 6, showing the work engaging devices and means for heating the same.

Figure 12 is a sectional view of the same parts on the line 12^a—12^a of Figure 4.

Similar reference characters throughout the several views indicate the same parts.

This invention, in the embodiment at present preferred as best illustrating the principles involved, is adapted for use as a forming press, but various other adaptations are contemplated, and the invention is by no means to be limited to the particulars of construction and operation of the embodiment herein shown and described for the purposes of the present disclosure. In this embodiment there is employed a support comprising an enclosing and supporting frame 15 having an upwardly extending portion 16 provided with a head 17 carrying work engaging or operating devices which in the present instance are dies 18, with which cooperate a plurality of similar operating devices or dies 19 on a movable element, or, more specifically, a rotary carrier, indicated generally at 20 and comprising a table which is intermittently rotated to bring the devices thereon successively to position for cooperation with the devices carried by head 17. The latter projects over the table for this purpose and mechanism is provided, as will appear later, for effecting relative movement of the devices on the head and table thus brought to cooperating position, toward and from each other, for operation on the interposed work.

Referring more particularly to Figures 3 and 4 the carrier table is indicated at 21, supported preferably on a frame 22 having a sleeve 23 fixed on a main rotary element or shaft 24 rotatable in bearings 25 and 26, supported by cross members of the main frame or support 15.

Carrier frame 22 is preferably provided on opposite sides with guide channels 27, Figure 7, in which are vertically movable cross-heads 28, each carrying on its upper portion one or more of the operating devices 19 and formed at its lower portion with a projecting lug 29 formed with an opening or bore with which is threadedly engaged an operating rod or bolt 30 adjustable on the cross-head by reason of its threaded connection therewith and having a nut 31 for locking the bolt in adjusted position. A cross brace 32 is fixed on each channel 27 and provided with a portion 33 embracing the corresponding bolt 30 for engagement with its head.

portion 34 to limit the downward movement thereof and of the cross-head, the purpose of this rod being to provide an operating means for raising the cross-head and the operating devices carried thereby for operation on the work.

The operating mechanism for the work engaging devices preferably comprises also a bearing sleeve 35 carried by the frame below the work engaging devices in which bearing is longitudinally movable a thrust rod or plunger 36 having at its lower end a yoke 37 in which is journaled a roller 38 cooperating with the surface of a cam 39 fixed on the upper side of a substantially disc shaped part 40 fixed on a sleeve 41 rotatable on the main shaft and supported at its lower end by collar 41^a. Attached to the upper end of sleeve 41 is a worm wheel 42 meshing with a worm 43 fixed on a shaft 44 rotated by mechanism hereinafter described, which imparts to sleeve 41 and the parts carried thereby continuous rotation about an axis concentric with the rotary main shaft and carrier. Disc 40 has an annular bearing flange 45 which rolls during the rotation of the disc on a thrust bearing comprising a roller 46 journaled on a bracket 47 supported on the main frame, and it will be obvious from the latter construction that as disc 40 is rotated, cam 39 carried thereby serves to actuate plunger 36 longitudinally for cooperation with the lower end of bolt 30 to raise the operating devices for operation on the work, the thrusting stress of these parts being supported by bearing roller 46 which at all times engages the under surface of the disc. It is apparent that these parts, as shown in Figure 4, are substantially in alignment with each other so that the stresses operate in a straight line between the bottom of the frame and head 17 supported thereby, affording a compact, substantial and rugged type of construction capable of exerting very considerable pressure on the work without deformation or breakage of the parts.

Positioning mechanism is provided for intermittently rotating the carrier or work table 21 to bring the devices carried thereby successively to position beneath the operating device carried by the head for cooperation with the latter, this mechanism comprising preferably a roller 48, Figures 4, 5 and 9, co-acting with a Geneva gear 49 rotatably supported on shaft 50, Figures 3, 5 and 9, carried in a bearing 51 at the bottom of the frame. This gear is preferably formed with radial channels 52 adapted to receive roller 48 which during rotation of disc 40 engages with one of these channels and rotates the gear through an angle of approximately 90 degrees, the gear being formed between the adjacent channel entrances with curved portions 53 co-acting

with a hub 54 on disc 40 to lock the gear against rotation, except when actuated by roller 48 opposite which the hub is formed with a depression 55 forming clearance for the projecting part 56 of the gear during such actuation. Connected with Geneva gear 49 and also on the shaft 50 is a spur gear 57 meshing with a gear 58 fixed on main shaft 24, by means of which the rotation of the Geneva gear rotates the main shaft and table 21 to bring the operating devices on the latter successively to position for cooperation with the operating devices on the frame, the table being locked by the Geneva motion between such intermittent rotation. With the present arrangement of operating devices on table 21, gears 57 and 58 have a two-to one ratio so that the table is rotated at each actuation through approximately 180 degrees.

A centering means is provided for securing registry between the devices on the work table and those on the frame, comprising a bearing sleeve 59 supported on a cross member of the main frame, in which is longitudinally slidable a spindle 60 carried by a bracket 61 fixed on the yoke 37 at the lower end of the operating plunger 36. Cooperating with spindle 60 are a pair of brackets 62, one on each side of the carrier and each formed with a socket to receive the spindle these parts being so arranged that the spindle engages one of the sockets just prior to upward actuation of the operating devices of the work table thereby centering the latter during cooperation with the work-engaging devices on the frame.

The actuating mechanism for imparting continuous rotation to sleeve 41 on the main shaft comprises, in addition to sleeve 41 and its associated parts, the shaft 44, previously described, which is journaled in a bearing 63 and is driven by the usual or any suitable system of a change speed gearing located in the casing 64, Figure 8, and controlled by means of a handle 65, this gearing however forming no part of the present invention and requiring no further description. A shaft 66 is provided for actuating the latter gearing and is driven from any suitable source of power, a pulley 67, Figure 2, being shown in the present instance for this purpose. It is apparent that as sleeve 41 is continuously driven the Geneva motion described rotates the main shaft intermittently to bring the work engaging devices on table 21 successively to position for cooperation with similar devices on the frame and centers and locks the table in such position for a brief period during which cam 39 raises plunger 36, and consequently the cross-head and operating devices carried thereby, for operation on the work. After each such operation the cross-head and work-engaging devices are lowered, and the carrier un-

locked and subsequently rotated to bring the succeeding pair of operating devices to position to repeat the operation during which the opposite devices are conveniently stationary at the front of the work table for the placing of the work thereon. The work may therefore be safely and expeditiously located on the table, in proper relation to the operating devices or dies, without requiring the operator to place his hands in the neighborhood of the active or cooperating dies, so that all danger of injury thereby is obviated.

Various operating devices may, of course, be employed with the present machine and are preferably detachably and interchangeably secured thereto by the usual or any suitable arrangement known to the art, the devices shown in conjunction with the present embodiment being dies mounted in pairs for accomplishing a forming or "doming" operation on a paper or fabric receptacle, and in performing such work it is at times desirable to provide means for heating the dies in order to render the work soft and pliable to facilitate the shaping operation. Accordingly the dies 19 on the work bed are provided with a heating means 68 which in the present instance is electrical in character, the wires extending from such means into a housing 70 secured at the center of the bed where they are provided with contacts or brushes 71, Figure 12, engaging rings 72 with which are connected wires 73 passing upwardly through a conduit 74 supported by a bracket on the head 17. Similarly the dies 18 on the frame are provided with heating means 75 to which current is supplied through wiring 76.

To facilitate the heating action of the dies cam 39 is provided with a profile comprising a rise 77 effecting a preliminary movement of the dies into proximity with the work, where they are permitted to remain for a short period by a flat portion or dwell 78 on the cam, the dies being subsequently raised and pressed against the heated work to form the same by the elevated portion 79 of the cam. In this manner the dies are first moved into proximity to the work where they remain long enough to heat and soften the latter, after which their movement is continued to complete the forming operation at the close of which they return by gravity to initial position.

The position of the dies on the work bed is adjustable through the threaded connection between the operating bolt 30 and the cross-head, to accommodate different working conditions, and to the same end the dies 18 on the frame are carried by a spindle 80 which is slideable in the head 17, the latter being of a split form of construction so that after longitudinal adjustment of the spindle 65 therein the head may be clamped in engage-

ment with the spindle by means of clamping bolts 81. The spindle carries a nut 82 below the head and also a wheel 83 above the head in threaded engagement with the spindle for vertical adjustment on the latter and of the dies carried thereby. Additional centering means for securing registry between the dies are provided in the cooperating pins 84 and sockets 85 provided in conjunction with the opposing dies.

The operation of the device is evident from the above description of its construction. The work is placed by the operator on the dies at the front of the work table 21 and the latter has imparted thereto an intermittent rotation through 180 degrees to bring the dies and work carried thereby to position for cooperation with the dies on the frame, and the devices thus brought to cooperating position are first raised adjacent the upper devices to heat and soften the work, and subsequently impressed on the latter to accomplish the forming operation. While one series of dies on the work bed is thus in operation, another series is at rest 90 at the front of the bed so that the work may be conveniently, rapidly and safely located on such dies in preparation for subsequent operation on it. As each series of dies is moved from operating position toward the front of the machine the completed work may thus be removed and new work be substituted or if desired the completed work may be automatically removed by a stripping device such as is well known in the art. 95 Various forms of operating devices or of dies may be employed in the machine, the parts for supporting such devices being adjustable to accommodate their varying dimensions. The operating parts are durable 100 in construction and positive in operation and the arrangement of the parts is such as to afford an exceedingly compact and strong construction. The arrangement of sleeve 41 and associated parts of the actuating means or mechanism in the substantially unitary and compact form disclosed concentric with the main rotary element or carrier shaft 24 materially reduces the number of parts and the size and weight of the machine.

We claim as our invention:

1. In a device of the class described, a support, an operating device thereon, a rotatable element on said support, a plurality of operating devices on said element, a continuously driven actuating part rotatably carried on said element, positioning mechanism actuated by said part for intermittently rotating said element to bring said devices thereon successively to position for cooperation with said device on the support, heating means for said devices, and operating mechanism actuated by said part for effecting relative movement of said cooperating devices first into proximity with the

work to heat the latter and subsequently into contact with the work to operate thereon.

2. In a device of the class described, a support, an operating device thereon, a movable element carried by said support, a plurality of operating devices on said element, actuating means comprising a part rotatably carried by said element, positioning mechanism actuated thereby for intermittently moving and locking said element to bring said devices thereon successively to position for cooperation with said device on the support, heating means for said devices, and operating mechanism actuated by said part for effecting a preliminary movement of the devices brought to cooperating position into proximity with the work to heat the latter and also a subsequent further movement thereof into operating engagement with the work.
3. In a device of the class described, a frame, an operating device thereon, a shaft rotatably carried by said frame, a plurality of operating devices connected with said shaft, actuating means comprising a part rotatably carried by said shaft, positioning mechanism comprising a Geneva movement connecting said part and shaft for intermittently rotating the latter to bring said devices thereon successively to position for cooperation with said device on the frame, and operating mechanism actuated by said part comprising a cam effecting a relative movement of the devices brought to cooperating position for operation on the work.

4. In a device of the class described, a frame, an operating device thereon, a shaft journaled in said frame, a plurality of operating devices connected with said shaft, a part rotatable on said shaft, a Geneva movement connecting said part and shaft for intermittently rotating and locking the latter to bring said devices thereon successively to position to cooperate with said device on the frame, and operating mechanism comprising a cam rotated by said part for moving the devices brought to cooperating position by the shaft into engagement with said device on the frame to operate on the work.

5. In a device of the class described, a frame, a shaft journaled therein, operating devices on said shaft and frame, an actuating part rotatably carried by said shaft, positioning mechanism connecting said part and shaft for intermittently rotating the latter to bring said devices thereon and on the frame successively to position for cooperation with each other, and operating means carried by said shaft and actuated by said part for effecting a relative movement of the devices brought to cooperating position for operation on the work.

6. In a device of the class described, the combination with a support, of an operating device thereon, an element rotatably mounted

on the support, a plurality of operating devices movable on said element, actuating means comprising a cam element rotatable concentrically with said element, mechanism actuated thereby for intermittently rotating said element to bring said devices successively into and out of position for cooperation with the device on the support, a thrust bearing on the support cooperating with said cam element and a plunger operatively engaged by the cam element for effecting movement thereof to operate the devices on the element into cooperation with the device on the support.

7. In a device of the class described, a support, an operating device thereon, a rotary element on the support, a plurality of operating devices movably carried by said element, actuating means rotating concentrically with relation to said element, positioning mechanism actuated by said means for intermittently rotating said element to bring said devices thereon and on the support successively to position for cooperation with each other, a plunger and thrust bearing on said support substantially in alignment with each other and with the devices brought to cooperating position, and a cam actuated by said means and engaging between said thrust bearing and plunger for moving the latter to effect operating movement of the devices on said element in cooperation with said device on the support.

8. In a device of the class described, a support, an operating device thereon, a plurality of operating devices movable successively into alignment with said device on the support, a rotary element, a cam supported and actuated thereby, operating means substantially in alignment with said aligned devices and actuated by said cam to effect relative movement of said aligned devices to operate on the work, and a thrust bearing engaging said cam opposite the point of engagement therewith of said operating means for relieving the stress on said rotary element.

9. In a device of the class described, a support, an operating device thereon, a movable carrier on said support, a plurality of operating devices on said carrier adapted to be brought by movement of the latter successively to position for cooperation with said device on the support, an operating member on said support effecting a relative movement of the devices in cooperating position for operation on the work and arranged substantially in alignment therewith, a bearing substantially in alignment with said member, a cam cooperating with said bearing and member for actuating the latter, and mechanism for moving said cam.

10. In a device of the class described, a support, a die thereon, a carrier movable on the support, a plurality of dies on said car-

- rier adapted to be brought by movement of the latter successively to position for co-operation with said die on the support, a plunger on said support effecting a relative movement of the dies in cooperating position for operation on the work and arranged substantially in alinement therewith, a bearing substantially in alinement with said member, a cam cooperating with said bearing and plunger for actuating the latter, 10 and mechanism for moving said cam.
- 5
- movement of the dies in cooperating position for operation on the work and arranged substantially in alinement therewith, a bear-
